(57) **CLAIM**

The ornamental design for a bungee cord organizer as shown and described.

DESCRIPTION

FIG. 1 is a perspective view of a bungee cord organizer showing my new design.

FIG. 2 is a front view of the bungee cord organizer of FIG. 1.

FIG. 3 is a back view of the bungee cord organizer of FIG. 1.

FIG. 4 is a right side view of the bungee cord organizer of FIG. 1.

FIG. 5 is a left side view of the bungee cord organizer of FIG. 1.

FIG. 6 is a top view of the bungee cord organizer of FIG. 1; and,

FIG. 7 is a bottom side view of the bungee cord organizer of FIG. 1.

The dot-dot-dash broken lines in the drawings depict a portion of the bungee cord organizer that forms no part of the claimed design.
